UNITED STATES PATENT OFFICE.

JOHN GARDNER, OF NEW HAVEN, CONNECTICUT, ASSIGNOR TO THE WINCHESTER REPEATING ARMS COMPANY, OF SAME PLACE.

DESIGN FOR A SOLID-HEAD CARTRIDGE-SHELL.

SPECIFICATION forming part of Design No. 26,677, dated February 23, 1897.

Application filed August 3, 1896. Serial No. 601,566. Term of patent 14 years.

To all whom it may concern:

Be it known that I, JOHN GARDNER, of New Haven, in the county of New Haven and State of Connecticut, have invented a new Design 5 for a Solid-Head, Metallic, Rimless-Cartridge Shell; and I do hereby declare the following, when taken in connection with the accompanying drawing and the letters of reference marked thereon, to be a full, clear, and exact 10 description of the same, and which said drawing constitutes part of this specification, and represents a side elevation of a solid-head, metallic, rimless-cartridge shell formed in accordance with my design.

15 This invention relates to a design for a solid-head, metallic, rimless-cartridge shell; and the design consists in the configuration of the shell, as shown in the accompanying illustration and hereinafter described.

20 My newly-designed solid-head, metallic, rimless-cartridge shell has its body A formed at a point near but slightly forward of its head A' with two shallow wave-like circumferential grooves or crinkles $a a'$, located at a right 25 angle to its longitudinal axis, the groove or crinkle a' being slightly narrower and also slightly shallower than the groove or crinkle a , and the two grooves being separated from each other by a distance fairly represented by 30 the width of the groove or crinkle a . The said body of the shell or case is very slightly tapered and is formed well toward its forward end with a long sloping bevel or shoulder A², which in turn merges into a long cylindrical

neck A³. The head A' of the shell is cylindrical and corresponds in diameter to the diameter of the rear portion of the body of the shell. The said head is encircled by an annular extracting-groove A⁴, having sharply-defined edges located at a right angle to the longitudinal axis of the shell and forming the line of demarcation between the body and the head thereof. This groove is deeper than either the groove or crinkle a or the groove or crinkle a' and is distinguished in particular therefrom by having sharply-defined edges and side walls of much sharper pitch. The extreme rear end of the head is beveled, as at A⁵.

35 The essential feature of my design lies in the shallow grooves or crinkles $a a'$ when formed and arranged as shown and when employed in conjunction with the deeper groove A⁴, having sharply-defined edges, and also in conjunction with the other features of the shell, as specified.

40 I claim—

45 The design for a solid-head, metallic, rimless-cartridge shell, as herein shown and described.

50 In testimony whereof I have signed this specification in the presence of two subscribing witnesses.

JOHN GARDNER.
